UNITED STATES PATENT OFFICE

153,908

DESIGN FOR A HEATER FOR FOOD PRODUCTS

Alexander F. Stolitzka, Summit, Ohio

Application February 10, 1948, Serial No. 144,385

Term of Patent 14 years

(Cl. D81—10)

To all whom it may concern:

Be it known that I, Alexander F. Stolitzka, citizen of the United States, residing at Summit County, in the State of Ohio, have invented a new, original, and ornamental Design for Heater for Food Products, of which the following is a specification, reference being had to the accompanying drawings, forming part thereof.

Fig. 1 is a perspective view of a heater for food products embodying my new design;

Fig. 2 is a top plan view of the heater;

Fig. 3 is a front view of the heater; and

Fig. 4 is a side view of the heater.

I claim:
The ornamental design for a heater for food products, as shown.

ALEXANDER F. STOLITZKA.
